UNITED STATES PATENT OFFICE.

JOEL W. JOHNSON, OF PINE BLUFF, ARKANSAS.

SPEEDOMETER-CONTROLLED IGNITION-CIRCUIT BREAKER.

1,223,177.

Specification of Letters Patent. Patented Apr. 17, 1917.

Application filed April 8, 1916. Serial No. 89,875.

To all whom it may concern:

Be it known that I, JOEL W. JOHNSON, a citizen of the United States, residing at Pine Bluff, in the county of Jefferson and State of Arkansas, have invented new and useful Improvements in Speedometer-Controlled Ignition-Circuit Breakers, of which the following is a specification.

This invention relates to speedometer-controlled ignition circuit breakers, the broad object of the invention being to produce means whereby when a speedometer such as is now commonly used in automobiles, indicates a certain predetermined mileage per hour, the ignition circuit will be automatically broken thereby throwing the internal combustion engine out of operation until the speed of the machine falls below the predetermined speed whereupon the ignition circuit will again be automatically closed, enabling the operator to proceed.

With the above and other objects in view, the invention consists in the novel construction, combination and arrangement of parts, as herein described, illustrated and claimed.

In the accompanying drawings:—

Figure 1 is a longitudinal section through the circuit breaker of this invention.

Fig. 2 is a view illustrating the face of a speedometer, also showing the circuit breaker, and the wiring plan.

The circuit breaker contemplated in this invention, in the preferred embodiment thereof, comprises the shell or tubular body 1 of brass or like material, the same being longitudinally bored throughout nearly the entire length thereof to receive a reciprocating core 2. The bore indicated at 3 is thus left open at one end to admit of the insertion and removal of the core 2 while the opposite end thereof is closed with the exception of a small central opening 4 through which is inserted a contact post 5.

At its inner end the post 5 is provided with a head 6 against which bears one end of a coiled expansion spring 7 the opposite extremity of which bears against the inner end of the slidable core 2.

Encircling the shell 1 is a solenoid coil 8 having one terminal thereof connected to a battery shown at 9 and the other terminal electrically connected to a contact 10 with which the pointer 11 of a speedometer des-

ignated generally at A is adapted to come in contact at a certain predetermined point. It will, of course, be understood that the contact 10 may be located at any point in order that the ignition circuit may be broken at any predetermined mileage per hour. The shell 1 also comprises a detachable section 12 which is internally threaded and screwed upon the open end of the main body 1 of the shell as indicated at 13. The opposite end of the shell section 12 is closed with the exception of a small central hole through which extends another contact post 14 corresponding with the post 5 but located at the opposite end of the circuit breaker. The post 14 is insulated from the member 12 by means of insulating washers 16 and 17 and an insulating sleeve or bushing 18. The circuit breaker is incorporated in the ignition circuit of which the contact posts 5 and 14 form parts when the sections of the circuit wires are connected thereto in any manner. The hand or pointer 11 is shown as sweeping over the face of a graduated dial A and this dial is illustrated as formed with a concentric slot 10' along which the contact piece 10 is shiftable so that it may be placed opposite any desired graduation. This makes the device adjustable to different speeds at which the ignition circuit will be broken.

From the foregoing description, taken in connection with the accompanying drawings, it will now be understood that up to the time the pointer 11 of the speedometer registers the predetermined mileage, the circuit through the circuit breaker remains unbroken. As soon, however, as the indicator or pointer 11 touches the contact 10, a current passes through the solenoid coil 8 and thereby retracts the core 2 against the tension of the spring 7. This breaks the contact in the ignition circuit and therefore no ignition takes place in the cylinder or cylinders of the engine until the speed is reduced below the predetermined mileage point, whereupon the current through the solenoid coil 8 is cut out and the ignition circuit is again closed by the operation of the spring 7 coacting with the core 2.

19 designates an ignition switch in the battery circuit, 20 represents the ignition box containing the usual ignition coil (not shown), 21 the distributor having a wire

connection with the induction coil in the ignition box, and 22 the ground wire leading from the ignition box.

Having thus described my invention, I claim:—

A speedometer-controlled ignition circuit breaker for the internal combustion engines of motor vehicles comprising in combination with a speedometer, a contact arranged 10 in the path of the movable indicator of said speedometer, a tubular shell made in two separable sections, contact posts at the opposite ends of said shell having heads arranged interiorly of the shell, a solenoid 15 coil surrounding said shell and having one terminal thereof in communication with the

contact of the speedometer, a slidable core mounted within said shell, a spring arranged within said shell and serving to yieldingly hold the core in contact with one 20 of said contact posts, said spring at its opposite end bearing against the head of the other contact post, and an electric circuit in which said solenoid coil is incorporated controlled by said movable indicator in 25 conjunction with said contact.

In testimony whereof I affix my signature in presence of two witnesses.

JOEL W. JOHNSON.
